D. G. ANDERSON

EXTENSION LEAF CONSTRUCTION FOR TABLES

Filed Feb. 23, 1926

UNITED STATES PATENT OFFICE.

DANIEL G. ANDERSON, OF LOS ANGELES, CALIFORNIA, ASSIGNOR TO ANDERSON COMPANY, OF LOS ANGELES, CALIFORNIA, A CORPORATION OF CALIFORNIA.

EXTENSION LEAF CONSTRUCTION FOR TABLES.

Application filed February 23, 1926. Serial No. 89,861.

This invention relates to an extension leaf construction for tables, in which a pair of oppositely disposed leaves are pivotally secured to the under surface of a table top and 5 are adapted to be slidably chambered therebeneath when not in use, and drawn outwardly into an extended position when in use.

A main object of the invention is to provide 10 a table extension leaf construction that may be easily applied to a certain type of table, such as a library table, without changing its characteristic design in the slightest, and when the leaves are drawn into an extended position the table will present the appearance of a table or another type, such as a dining table.

A further object is to provide an extension leaf construction for tables that will 20 obviate the use of spring catches, catch plates, and pull chains, or cables for operating the catches when it is desired to bring the leaves into an extended position.

Other objects and advantages will be apparent 25 from the following specification, reference being had to the accompanying drawings forming a part thereof, in which—

Fig. 1 is a top plan view of a table equipped 30 with extension leaves in an extended position.

Fig. 2 is a bottom plan view of the table shown in the above view showing one leaf extended and the other concealed below the top.

Fig. 3 is an enlarged cross section taken 35 on line 3—3 of Fig. 2.

Fig. 4 is an enlarged longitudinal section through the table top taken on line 4—4 of Fig. 3.

Fig. 5 is a detail sectional view of the leaf supporting slide taken on line 5—5 of Fig. 4.

Fig. 6 is an enlarged detail sectional view showing the hinge construction.

Fig. 7 is a similar view taken on line 7—7 of Fig. 6.

Referring now specifically to the drawings it will be seen that the table illustrated consists of a table top 10, of the stationary 50 type used in the formation of "library" or living room tables, of elongated form having secured to the under face adjacent each end supporting legs 11, 12, terminating in the usual bases, not shown. Secured to the 55 under face of the table top and adjacent its

edges are depending aprons 13, 14, 15, 16, designed primarily to conceal from view the extension leaves 17, 18, when chambered beneath the top. These leaves are of elongated form having straight meeting edges 19, 20, 60 and rounded outer ends 21, 22, to correspond with the segmental ends of the top. Extending transversely of the table top 10, their ends being secured to the oppositely disposed faces of the aprons 13, 14, are a plurality of 65 cylindrical guide rods 25, arranged in pairs between the table legs, a pair adjacent each end of the table. These guide rods are designed to be engaged by a member of the leaf hinges 26, in order that the leaves to 70 which they are attached may be slidably moved into or out of position with respect to the table top. These hinges 26 preferably consists of an attaching member 27 secured by screws to the table meeting edge of the 75 extension leaf 17, as best shown in Fig. 6, and pivoted thereto is the other hinge member 28 which consists of a downwardly extending curved portion terminating in an angular outer end provided with a circular 80 rod engaging aperture 29 of a diameter slightly larger than the rod in order that it may move freely thereon without a binding movement. The curved and angular form of this hinge member is to enable the hinge 85 member to extend under and around the apron 13, when the leaf is in the extended form.

In order to rigidly support the leaves when in their extended positions slide bars 90 30 are provided. These bars are mounted in grooved guide bars secured to the under face of the table top midway between the table ends, the outer end of the bars passing through openings 31 formed in the aprons 95 13 and 14 of the table top when drawn into supporting position. The outer edges of the bars are provided with stops 32, their inner ends also being provided with similar stops 33, said stops limiting the inward and outward movement of the bars. 100

The extension leaves when not in use are chambered directly beneath the table top, as shown in Fig. 3 of the drawings, the inner ends of the leaves engaging ledges 34 and 35 105 secured to the oppositely disposed faces of the table legs directly below the aprons. The upper surfaces of these leaves bear directly against the hinge guide rods 25 which serves to prevent their accidental disengage- 110

ment from the ledges 34 and 35 when in their chambered position. When it is desired to extend the table top the leaf is pulled forwardly until free of the ledges and allowed to swing downwardly into the position shown in dotted lines in Fig. 3, the member 28 of the hinge sliding along the rod. The leaf is then drawn upwardly until it engages the side edge of the table top, 10 the curved configuration of the hinge member permitting of such movement around the apron 14. The operator may then pull the slide bar 30 forwardly into position for rigidly supporting the leaf.

15 What I claim is:

1. An extension table including a stationary table top, depending aprons around the edge of the table top, a leaf movable with relation to the table top and having an edge 20 adapted to register with the table top edge, guide rods secured to the table beneath the table top, hinges for the leaf including a hinge member slidably mounted on one of said rods and a second hinge member secured 25 to the leaf near its said top meeting edge, the first mentioned hinge member adapted to extend under and around the depending apron of the table top.
2. An extension table including a stationary table top, depending aprons around the edge of the table top, a leaf movable with relation to the table top and having an edge 30 adapted to register with the table top edge, hinge guide rods secured to said table beneath its top, hinges for the leaf embodying a hinge member slidably secured to one of said guide rods, and a second hinge member secured to the leaf near its said top meeting edge.
3. An extension table including a stationary table top, depending aprons around the edge of the table top, a leaf movable with relation to the table top and having an edge 35 adapted to register with the table top edge, hinge guide rods secured to the table beneath its top, hinges for the leaf including a hinge member slidably secured to one of the guide

rods and a second hinge member secured to the free end of the first mentioned hinge member and to the leaf near its said top meeting edge, the first mentioned hinge member adapted to extend under and around the depending aprons of the table top, and means formed on said table for supporting the leaf beneath the table top when not in use.

4. An extension table including a stationary table top, a leaf movable with relation to the table top and having an edge adapted to register with the table top edge, depending aprons secured to the table top around its edges, a plurality of guide rods secured to a pair of oppositely disposed aprons beneath the table top, a pair of hinges for the leaf including a hinge member having one end slidably mounted on one of said guide rods, 65 a second hinge member secured to the leaf adjacent its table top meeting edge, the first mentioned hinge member being bent into angular formation and adapted to extend under and around the depending apron of 70 the table top when the leaf is in its extended position, and horizontally disposed members secured to the oppositely disposed faces of the table legs below the table top for receiving and supporting the inner ends of 75 the extension leaves when chambered beneath the top.

5. An extension table including a stationary table top, depending aprons secured to the table top around its edges, a leaf movable with relation to said table top having an edge adapted to register with the table top edge, and hinges for the leaf, one leaf of each of said hinges being secured to the table top leaf adjacent its table top meeting edge 80 and the other leaves of said hinges slidably secured to the underface of the table top for moving the leaf in a plane parallel to the table top and around the depending apron on a chambering or extending operation.

In witness that I claim the foregoing I have hereunto subscribed my name this 22nd day of January, 1926.

DANIEL G. ANDERSON.
